UNITED STATES PATENT OFFICE.

ROBERT MILLS, OF NEWTON, ASSIGNOR TO DENMAN BLANCHARD, OF MELROSE, MASSACHUSETTS.

DESIGN FOR A CASE FOR VENDING-MACHINES.

SPECIFICATION forming part of Design No. 22,126, dated January 10, 1893.

Application filed November 21, 1892. Serial No. 452,732. Term of patent 14 years.

To all whom it may concern:

Be it known that I, ROBERT MILLS, a citizen of the United States, residing at Newton, in the county of Middlesex and State of Massachusetts, have invented a new and original Design for a Case for Vending-Machines, of which the following is a specification.

The two figures in the drawings represent opposite perspective views of the design, and similar letters of reference in them indicate corresponding parts.

The base A is rectangular in horizontal section and is substantially of ogee shape in vertical section. The lower portion or main body next the base is essentially rectangular in section and consists of the upright corner pieces B and recessed panels C as shown. The cap D of this portion overhangs and has substan-

tially spherical knobs E near its corners. Upon the cap D sets the upper portion of the body substantially rectangular in section and with recessed panels F as shown. Extending from its upper front edge is a concavo-convex plate H for receiving an inscription of directions; and extending up from the rear side is an extension or upright, which is vertical near its base at I and at J bends forward over the plate H.

I claim

The design for a case for vending machines as herein shown and described.

ROBERT MILLS.
